UNITED STATES PATENT OFFICE.

JOHN F. O'CONNOR, OF CHICAGO, ILLINOIS, ASSIGNOR TO WILLIAM H. MINER, OF CHICAGO, ILLINOIS.

RAILWAY DRAFT-RIGGING.

1,125,384.

Specification of Letters Patent.

Patented Jan. 19, 1915.

Application filed March 4, 1914. Serial No. 822,406.

To all whom it may concern:

Be it known that I, JOHN F. O'CONNOR, a citizen of the United States, residing at Chicago, in the county of Cook and State of Illinois, have invented a certain new and useful Improvement in Railway Draft-Rigging, of which the following is a full, clear, concise, and exact description, reference being had to the accompanying drawings, forming a part of this specification.

My invention relates to improvements in draft rigging for railway cars.

The object of my invention is to provide a strong and efficient draft rigging for rail-way cars, and one in which a high spring capacity may be obtained.

In the accompanying drawings forming a part of this specification, Figure 1 is a side elevation of a draft rigging embodying my invention; Fig. 2 is a plan view partly in horizontal section on line 2—2 of Fig. 1, and showing the parts in normal position; Fig. 3 is a cross-section taken on line 3—3 of Fig. 1; Fig. 4 is a plan view partly in horizontal section, showing the position of the parts with the intermediate spring fully compressed, and the follower springs engaging their respective stop-shoulders in buffering movement; Fig. 5 is a plan view partly in horizontal section, showing the position of the parts in full buff.

Referring to the drawings, the numerals 6—6 represent draft-sills or parts of the car-frame to which the draft rigging is applied.

7 represents a tie plate suitably secured to the draft-sills by the bolts 8—8, and adapted to support the draft-gear 9 which is mounted between the draft-sills 6. The draft-gear 9 is inclosed by the draft-yoke 10, which is suitably connected to the draw-bar 11, only the rear end of the draw-bar being shown in the drawings.

The numerals 12—12 represent counter-part stop members secured by suitable means, preferably the rivets 13—13, to the draft-sills. The stop members 12 are provided with the front stop-shoulders 14—14, the rear stop-shoulders 15—15, the rear intermediate stop-shoulders 16—16, the front-intermediate stop-shoulders 17—17, the front spring stop-shoulders 18—18, the rear spring stop-shoulders 19—19, the rear intermediate

spring stop-shoulders 20—20, and the front intermediate spring stop-shoulders 55 21—21.

The draft-gear 9 is preferably of the spring type, and comprises the transversely hollow front follower 22, the flat springs 23 therein, the transversely hollow rear follower 24, and the flat springs 25 therein, and the intermediate spring member 26. The transverse opening 27 in each of the followers is formed between the front wall 28 and the rear wall 29, each of said walls 65 being convex in relation to the flat springs passing through the said opening when the springs are straight and in their normal position as illustrated in Fig. 2 of the drawings. The flat springs in each follower are 70 preferably composed of a plurality of flexible flat steel plates 30—30, the front set of springs 23 projecting at its ends beyond the front follower, the ends of said springs being adapted to engage the front spring stops 75 18 on forward movement of the draw-bar, and the rear intermediate spring stops 21 on rearward movement of the draw-bar. Similarly the rear set of springs 25 projects at its ends beyond the rear follower 24, and is 80 adapted to engage the rear spring stop-shoulders 19 on rearward movement of the draw-bar, and the rear intermediate spring stop-shoulders 20 on forward movement of the draw-bar. The front follower is provided with a preferably integral rearwardly 85 extending boss 31, and the rear follower is provided with a preferably integral forwardly extending boss 32, the bosses 31 and 32 being suitably aligned and of suitable 90 length to permit their engagement and limit the compression of the spring member 26. The intermediate spring member 26 preferably comprises an inner coil 33 and an outer coil 34, the said coils being seated at their 95 ends against the inner faces of the followers. In preferable construction, the flat spring members 23 and 25 in their respective followers are of greater capacity than the spring member 26 seated between the followers. 100

In normal position of the parts of the gear, the forward flat springs 23 engage the front spring stops 18, a short space 35, as illustrated in Fig. 2 of the drawings, being 105 maintained between the forward face of the

front follower 22 and the front stop-shoulder 14; also in the normal position of the gear, the rear springs 25 are in engagement against the rear spring stop-shoulders 19, 5 there being a slight space 36, as illustrated in Fig. 2 of the drawings, between the rear face of the rear follower 24 and the rear stop-shoulders 15. On rearward movement of the draw-bar, initially the rear springs 25 10 remain stationary and substantially in their normal straight position, holding the rear follower 24 as a stop for the intermediate spring member 26, the same being compressed against the rear follower by the 15 rearward movement of the front follower. Upon the engagement of the boss 31 of the front follower with the boss 32 of the rear follower, and the limiting thereby of further compressing movement of the spring member 26, the flat springs 23 in the front follower engage the forward intermediate spring stops 21. At this point in the rearward movement of the front follower a slight space 37 remains between the rear 20 face of the front follower 22 and the rear intermediate stop-shoulders 17, the said space being substantially equal to the space 36 between the rear follower and the rear stop-shoulders 15. The position of the parts at 25 this point of the rearward movement is illustrated in Fig. 4 of the drawings. Upon further rearward movement of the draw-bar, the springs 23 through the front follower are flexed against the convex forward wall 28 within the follower, and the rear springs 25 are flexed against the convex forward wall 28 of the rear follower 24 until the front follower engages the front intermediate stop-shoulder 17, and the rear follower 30 engages the rear stop-shoulders 15, when the buffing movement of the gear will be complete and the parts will be in the position illustrated in Fig. 5 of the drawings. On forward movement of the draw-bar, the 35 front flat springs 23 are in engagement against the front spring stop members 18 holding the front follower 22 as a stop against the forward movement of the intermediate spring member 26, there being the 40 space 35 between the front face of the front follower 22 and the front stop-shoulders 14. The intermediate spring member 26 is compressed by the forward movement of the yoke drawing the rear follower 24 forwardly until the boss 32 of the rear follower 45 engages the boss 31 of the front follower. Upon such engagement the rear springs 25 carried within the rear follower 24 engage the rear intermediate spring stop-shoulders 50 55 60 65 70 75 80 85 90 95 100 105 110 115 120 125 130

front stop-shoulders 14. On further forward movement of the draw-bar, the intermediate spring member 26 moves forwardly without further compression between the followers, and the front flat springs are compressed against the convex rear internal face 29 in the front follower until the front follower engages the front stop-shoulders 14, and meanwhile the rear springs 25 within the rear follower 24 are flexed against the convex rear face 29 within the rear follower 24 until the rear follower engages the rear intermediate stop members 16, whereupon the forward movement of the gear is complete.

I claim:—

1. In a draft rigging for railway cars, in combination, stop-members, followers, springs between the followers, springs projecting from the followers, the stop-members being provided with stop-shoulders for said last mentioned springs, and with stop-shoulders for the said followers.
2. In a draft rigging for railway cars, the combination with stop members of a draft-gear comprising followers, a compression-resisting member between the followers and springs, the springs extending at either end from the followers, the stop-members being provided with stop-shoulders for said springs, and with stop-shoulders for said followers, the engagement of the followers with said stop-shoulders limiting the flexing of the springs.
3. In a draft rigging for railway cars, the combination with stop-members having front, rear, front intermediate and rear intermediate follower stop-shoulders, and front, rear, and front intermediate and rear intermediate spring stop-shoulders, of followers, a compression-resisting member between the followers, and springs laterally extended at either end from the followers.
4. In a draft rigging for railway cars, the combination with stop-members having front, rear, front intermediate and rear intermediate follower stop-shoulders, and front, rear, and front intermediate and rear intermediate spring stop-shoulders, of followers, a compression-resisting member between the followers, and springs laterally extended at either end from the followers, the springs in the movements of the draft-gear engaging the spring stop-shoulders before the followers engage the stop-shoulders.
5. In a draft rigging for railway cars, in combination, stop-members, followers, springs between the followers, transversely extending springs adapted to be flexed by the followers upon movement of the latter, said stop members being provided with stop-shoulders for such transversely extending springs and with stop-shoulders for the followers.

6. In a draft rigging for railway cars, the combination with a transversely extending spring, of a stop member provided with spaced follower stop-shoulders, one of which is an intermediate stop-shoulder, said stop member being provided also with another pair of stop-shoulders inset below said first named shoulders, the last named stop-shoulders being adapted to serve as shoulders for said transversely extending springs.
